UNITED STATES PATENT OFFICE.

AMBROSE RIDD, OF NEWPORT, KENTUCKY.

POLISHING DEVICE FOR ROLLS.

No. 881,684.

Specification of Letters Patent.

Patented Sept. 25, 1906.

Application filed September 21, 1905. Serial No. 279,536.

To all whom it may concern:

Be it known that I, AMBROSE RIDD, a citizen of the United States, residing at Newport, in the county of Campbell and State of Kentucky, have invented a new and useful 5 Polishing Device for Rolls, of which the following is a specification.

This invention relates to metal-rolling mills, and particularly to mills for rolling 10 sheet metal where it is desirable to keep the surfaces of the rolls absolutely clean and free from foreign substance, such as particles of dirt or oxid, which might cling to the rolling-surfaces and mar the surface of the passing 15 sheet.

The principal object of the invention is to provide a means for keeping the surface of the mold perfectly clean, smooth, and polished.

20 A further object of the invention is to provide a polishing device to be applied to a roll throughout the rolling operation.

A still further object of the invention is to provide a novel form of polishing device and 25 to provide a novel means for holding such polishing device against the surface of the roll or rolls.

With these and other objects in view, as will more fully hereinafter appear, the invention 30 consists in certain novel features of construction and arrangement of parts, hereinafter fully described, illustrated in the accompanying drawings, and particularly pointed out in the appended claims, it being 35 understood that various changes in the form proportions, size, and minor details of the structure may be made without departing from the spirit or sacrificing any of the advantages of the invention.

40 In the accompanying drawings, Figure 1 is an elevation of a pair of rolls provided with cleaning and polishing devices constructed in accordance with the invention, the front housing being removed. Fig. 2 is a vertical 45 section of one of the polishing devices, drawn to an enlarged scale. Fig. 3 is a detail sectional view of a portion of a modified construction of polishing device.

Similar characters of reference are employed 50 to indicate corresponding parts throughout the several figures of the drawings.

In some classes of metal rolling, particularly on sheet-metal mills, it is necessary to 55 stop the rolling operation at intervals and burnish the rolls. Perfect rolling can be ac-

complished only with clean rolls, and any particles of dirt or oxid scale that may cling to the rolls will be embedded in the sheets, materially detracting from the appearance and 60 the value of the sheets. In carrying out the present invention a cleaning and polishing device is applied to each of the rolls and is held against such roll during the entire rolling operation, or provision may be made for 65 applying it only at intervals.

The rolls A and housing B illustrate a conventional form of mill.

The housings are provided with supports 10 for a transversely-extending casing 11, that 70 is provided with upper and lower flanges 12, and the rear face of the casing is connected by a tube 13 to a source of fluid-pressure supply, preferably steam.

The flanges 12 serve as supports for the 75 polishing device 14, which is preferably formed of a material which will withstand high temperature without injury, asbestos or a compound containing asbestos being 80 preferably employed, and in order to hold the asbestos in place it may be interwoven with or otherwise supported by layers 15 of wire gauze or netting. This polishing member has a backing-plate 16, preferably formed of flexible metal; and the central portion of 85 the plate is of much thinner gage than the end portions, the ends being preferably heavy and unyielding and being provided with rearwardly-extending flanges 17, between which and the flanges 12 are arranged 90 packing-strips 18, that will prevent the escape of the fluid.

In operation the fluid, preferably steam, is admitted through the pipe 13, and the interior of the casing 11 constitutes a pressure-cylinder, the plate 16 forming a piston or diaphragm that is pressed outward by the steam, and as the central portion of this plate is thinner and more elastic than the edge portion said central portion will bend or bulge 95 in the direction of the roll and the cleansing or polishing pad 14 will be held firmly against the surface of the roll.

The rolls are usually heated, and it is therefore preferred to employ asbestos or some 105 similar substance for the cleansing or polishing pad, this material being capable of withstanding high temperature without injury, and it is also preferred to employ steam as the forcing or pressing agent, the steam being 110 also at a high temperature and being usually convenient in a mill. In some cases,

however, air or a liquid under pressure may be utilized, and springs may also be employed as a substitute for the fluid.

In the construction shown in Fig. 3 the upper and lower edges of the cleaning and polishing pad are firmly secured to the edge flanges 12' of the casing, so that the central portion only will bulge outward.

With a device constructed in accordance with this invention the surface of the rolls may be kept perfectly smooth and clean, and the resultant sheets will be of more uniform character, and their surfaces will be free from indentations and imperfections which result from the clinging of particles of oxid scale or dirt to the rolling-surface.

Having thus described the invention, what is claimed is—

1. A cleaning device for use in connection with rolling-mill rolls *in situ*, comprising a cleaning or polishing pad, and a fluid-pressure means for forcing the same into contact with the roll.

2. A cleaning device for use in connection with rolling-mill rolls *in situ*, comprising a

polishing-pad of a length approximately equal to that of the roll and having a concaved face, and a fluid-pressure means for forcing the same against the surface of the roll.

3. A roll-polishing pad, formed of a yieldable material, an elastic metallic plate forming a backing therefor, a casing in which said plate is arranged, and means for admitting a fluid under pressure to said casing.

4. A roll-polishing pad formed of a yieldable material, a backing-plate for the pad, said plate being thinnest at the center, and gradually thickening toward its opposite edges, a cylinder-like casing having upper and lower flanges for the support of the plate and pad, and means for admitting a fluid under pressure to the interior of said casing.

In testimony that I claim the foregoing as my own I have hereto affixed my signature in the presence of two witnesses.

AMBROSE RIDD.
